CLAIM

An ornamental design for a data and sensor system hub, as shown and described.

DESCRIPTION

FIG. 1 is a front perspective view of a data and sensor system hub according to our new design;

FIG. 2 is a front view of a data and sensor system hub thereof;

FIG. 3 is a rear view of a data and sensor system hub thereof;

FIG. 4 is a right side view of a data and sensor system hub thereof;

FIG. 5 is a left side view of a data and sensor system hub thereof;

FIG. 6 is a top view of a data and sensor system hub thereof; and,

FIG. 7 is a bottom view of a data and sensor system hub thereof.
